US00D575262S

(12) **United States Design Patent**
Brown et al.

(10) **Patent No.:** **US D575,262 S**
(45) **Date of Patent:** **** Aug. 19, 2008**

(54) **TELEPHONE**

(75) Inventors: **Dustin Brown**, Chicago, IL (US);
Arthur Wu, Plano, TX (US); **Chris**
Hunke, Plano, TX (US); **Shingo**
Ishizaka, Tokyo (JP); **Akira Takahashi**,
Tokyo (JP)

(73) Assignee: **Iwatsu Electric Co., Ltd.**, Tokyo (JP)

(**) Term: **14 Years**

(21) Appl. No.: **29/298,108**

(22) Filed: **Nov. 29, 2007**

(51) **LOC (8) Cl.** **14-03**

(52) **U.S. Cl.** **D14/151**

(58) **Field of Classification Search** **D14/130, D14/140–142, 144, 146–151, 158–159, 240, D14/243, 251–253, 329–330, 357, 434, 496; 379/88.17, 90.01, 93.17, 387.01, 388.02, 379/419–420.04, 420.02, 428.01–428.04, 379/434–436, 440, 446–447, 454–455; 381/16, 381/71.1; D13/107–108; 191/12.2 R; 320/108, 320/110, 113–115; 455/411, 550.1–90.3; 348/14.01–14.06**
